Attorney

UNITED STATES PATENT OFFICE.

CHAUNCEY D. NELLIS, OF ROSENDALE, WISCONSIN.

INFLATING VALVE STRUCTURE FOR BASKET BALLS AND THE LIKE.

Application filed June 3, 1924. Serial No. 717,570.

To all whom it may concern:

Be it known that I, CHAUNCEY D. NELLIS, a citizen of the United States, residing at Rosendale, in the county of Fond du Lac and State of Wisconsin, have invented certain new and useful Improvements in Inflating Valve Structures for Basket Balls and the like, of which the following is a specification.

10 This invention relates to improvements in the construction of a basket ball and the like, and particularly the provisions made therein for inflating the same.

An object of the invention resides in providing a basket ball bladder with an inwardly directed neck portion adapted to receive a valve member to be housed therein and within the cover of the basket-ball.

Another object of the invention is to provide a basket ball having a special inflating structure for the bladder thereof, wherein the bladder is provided with an inwardly directed neck portion for receiving a sleeve like valve housing containing a suitable valve for permitting the entrance of air to the bladder, but preventing the exhaust thereof under normal conditions, and providing a plate mounting said tubular valve housing adapted to extend between the cover and the bladder for holding said valve housing in a predetermined relation with the cover when inflated, and for protecting the connection of the valve and the neck with the remaining portion of the bladder.

35 The invention includes other objects and improvements in the details of construction and arrangement of the parts, which are more particularly pointed out in the following detailed description, and in the 40 claims directed to a preferred form of the invention, it being understood, however, that various changes in the size, form and arrangement of these parts may be made, without departing from the spirit and scope of 45 the invention as described and claimed.

In the drawings, forming part of this application:

Figure 1 is a partial sectional view, through a basket ball showing the inflating structure thereof, constructed according to the invention.

Figure 2 is an elevational view of the structure shown in Figure 1.

50 The cover for the basketball or the like is indicated at 1, and which, as usual is provided with a slotted portion 2, to permit the

insertion and removal therein of the reinforcing liner 3 and the usual inflating bladder 4. A reinforcing strip 5 is usually provided between the liner and the bladder at 60 the portion overlying the slotted portion 2 of the cover 1, in order to prevent the bladder from bulging outwardly through the slotted portion, which is laced, together, by suitable lacing as indicated generally at 6, 65 while the cover 1 is usually reinforced around the slotted portion 2, as indicated by the dotted line 7, in Figure 2.

The bladder 4 is formed with an inwardly directed inflating neck 8, which receives the 70 valve housing 9, of tubular form, which is formed on the inner end thereof with a plurality of ribs 10, on the outer periphery, adapted to effect the stretching of the neck for insuring the firm positioning of the 75 valve member in the same. The outer end of the tubular valve housing 9 is seated in the opening in the central portion of an elongated plate 11, positioned between the cover 1 and the lining 3, and normally positioned at substantially right angles to the position of the slot 2, in the manner clearly shown in the drawing. The end portions of this plate are rounded, as indicated at 12, and the same is curved to conform to 80 the curvature of the ball, in inflated relation, while the central portion of the plate is enlarged as indicated at 13, and slightly concaved as shown in Figure 1. The cover 1 is formed with an opening 14, the size of 85 the valve housing 9, said valve housing being formed with internal threads 15 in the outer end thereof for receiving a cap 16, adapted to be screw threaded in the outer end of the housing, for preventing dust and 90 dirt from entering the same in the use of the ball, after the same is inflated, and also for receiving the usual threaded nipples carried by the ends of an inflating device, so that the same may be connected thereto, for 95 inflating the ball.

A threaded member 17 is threaded into the housing 9, cooperating with the threads 15, as shown in Figure 1 and formed with a central opening for guiding the valve stem 105. 18 carrying at the inner end thereof a valve 19, adapted to seat in the valve seat member 20, formed with a partition and valve seat for said valve 19, so that when the valve is seated therein, the air in the ball will be 110 prevented from gaining an exit. A coil spring 21 surrounding the valve member 19

between the seat 20 and the member 17 seats at one end on the member 20 and normally acts to cause said valve 19 to engage its seat, by the expansive action thereof on the 5 valve stem 18, through engagement with the cross pin 22. A head 23 is provided on the free end of the valve stem 18, and outwardly of the member 17, so that the same may be operated for unseating the valve 19 to permit 10 the air in the ball to be exhausted.

From the foregoing description, it should be clear that a valve structure for basketballs or other forms of playing balls, which are inflated for use in playing games has 15 been provided, which will permit the ready application of an inflating device for supplying air to said ball to inflate the same, and which will normally prevent the exhaust of said air, as well as providing means 20 which is readily operable to permit the exhaust of the air through manual operation to unseat the valves, when desired.

What is claimed is:

1. A structure of the class described comprising a cover member, a bladder within 25 said cover having an inwardly directed neck formed thereon and adapted to contain air under pressure for inflating said cover, a valve housing mounted in said neck and 30 having the outer end thereof projecting into an opening in said cover, a valve member in said housing normally operable for closing the passage therethrough, an elongated plate member having an enlarged slightly 35 concaved central portion formed with a central opening receiving said valve housing

and positioned between the bladder and cover for holding said housing in a predetermined relation thereto, and a cap adapted 40 for removable connection with the valve housing for closing the passage there-through.

2. A device of the class described, comprising a cover, a bladder within said cover having an integrally formed neck portion 45 directed inwardly thereon, a valve housing formed with a plurality of peripheral ribs seated in the neck portion of the bladder, and having the outer end thereof extending into an opening in the cover, a seat member 50 mounted in said valve housing, a valve stem extending in the central portion of said housing and carrying a valve for engaging said seat, resilient means positioned between the seat member, and projections on said valve stem for normally holding said valve 55 in engagement with the seat, the outer internal end portion of said valve housing being provided with a threaded portion 60 adapted to receive a closure cap and nipple on an inflating device, and an elongated plate member having a central opening 65 therein receiving the outer end of said valve housing and mounting the same therein positioned in angular relation with the slotted portion formed in the cover and between said cover and bladder for normally maintaining said valve housing in a predetermined relation in said cover.

In testimony whereof I affix my signature. 70

CHAUNCEY D. NELLIS.
